CLAIM

The ornamental design for a tablet crusher, as shown and described in the drawings.

DESCRIPTION

FIG. 1 is a side top perspective view of a tablet crusher of the present invention;

FIG. 2 is a first side elevation view of the tablet crusher of the present invention;

FIG. 3 is a second side elevation view of the tablet crusher of the present invention;

FIG. 4 is a third side elevation view of the tablet crusher of the present invention;

FIG. 5 is a fourth side elevation view of the tablet crusher of the present invention;

FIG. 6 is a top plan view of the tablet crusher of the present invention;

FIG. 7 is a bottom plan view of the tablet crusher of the present invention; and,

FIG. 8 is a side bottom perspective view of a tablet crusher of the present invention.

Shown in phantom lines in FIGS. 1 and 6 are optional attachment screws used with the tablet crusher of the present invention. Also shown in phantom lines in FIGS. 7 and 8 are optional base feet portions that may be used with the tablet crusher of the present invention. These aspects form no part of the claimed design, but are used to illustrate the optional attachments thereto.
